APPARATUS AND PROCESS FOR MAKING
FILAMENTS

Edward E. Lovig, Chicago, Ill.

Application May 4, 1945, Serial No. 591,904

10 Claims. (Cl. 28—76)

1

This invention relates to novel filaments and their manufacture.

It is an object of my invention to produce a synthetic filament which, when placed alongside and together with like filaments, will interlock therewith so that a number of strands or the same continuous piece of filament may be collected and bunched together to form a product which is substantially shape retaining and resilient and can be used for liquid and gas filtering, heat insulation, padding, and other purposes.

A further object is to provide novel apparatuses and processes for producing any one or more types of filaments having these characteristics.

It is also an object of my invention to provide a filament which is kinked at relatively short intervals throughout the length thereof.

Another object is to provide a filament which is kinked at irregular intervals throughout the length thereof.

Further objects and advantages of my invention will appear as the description proceeds.

The invention will be better understood upon reference to the following description and the accompanying drawings, in which:

Fig. 1 is a side perspective view of an apparatus constructed in accordance with my invention.

Fig. 2 is an opposite side and top perspective view of the same.

Fig. 3 is an enlargement of a portion of Fig. 2.

Fig. 4 is a front perspective view of the complete structure.

Fig. 5 is a longitudinal diagrammatic sectional view of the same.

Fig. 6 is an enlarged elevational view of a traction roller and associated mechanism.

Fig. 7 is a view, partly in section, and magnified about thirty times, of a portion of a filament according to my invention.

Fig. 8 is a diagrammatic view of an electrically heated crimp roller according to my invention.

Fig. 9 shows in single line form a portion of a filament after it has been crimped but before being kinked.

Fig. 10 shows in single line form a portion of a filament after it has been crimped and kinked.

In the manufacture of air filters, it has been the custom to use hair, sisal grass, sisal hemp, Tampico hemp, wire and other materials. Hair is resilient and does not pack excessively and can be curled so that when used as a filter and in proper lengths it is fairly efficient. However, it is smooth and hence oil does not adhere to it very well and particles in the air slip by. Moreover hair is quite expensive and is scarce in

lengths sufficiently great to be efficient. Sisal grass, sisal hemp and Tampico hemp are quite stiff and smooth and require expensive processing and come in shorter lengths than desired. Wire has been found no more efficient than hair. Other materials have been used but they have been found unsatisfactory for various reasons.

I have discovered that a filament can be made which can be used as a filter material and for other purposes, of which those noted above are examples, and, when so used, is more efficient and much less expensive than materials heretofore used for such purposes. My invention embraces not only a novel filament but also unique apparatuses and processes for making the filament in various forms according to the uses to which it is to be put.

In practicing one form of my invention, I start with a strand consisting entirely of vegetable fiber of substantial cellulose content, of which cotton is an example, or of a mixture of cellulose with a synthetic fiber, of which examples are rayon and nylon. A filament which is to be used as an air filter, for example, should be resilient, among other things. Increasing the number of plies with the same tightness of twist increases its resilience but the cost is also greatly increased. Increasing the tightness of twist or spin with the same number of plies increases the resilience but decreases the yardage per unit weight. If I start with a loosely spun single-ply mixture of approximately equal parts of cotton and synthetic fiber, I can obtain the same yardage and resilience as is obtainable with a triple-ply tightly spun all-cotton strand at about one-half the cost at present day prices. Such a mixture may be spun loosely but enough to hold the fibers together so that there will be sufficient strength in the composite strand to withstand the pulls to which it will be subjected in the process of making the filament to which this invention relates. This composite material, as noted above, is very much cheaper than an all-cotton material, for the same end results. One reason for this is that the synthetic fiber has the property of imparting resilience to the finished product, and thus obviates the cost of spinning operations inherent in multiple-ply strands. The percentage of synthetic fiber, the tightness of twist and the number of plies of the mixture strand may be varied as desired according to the purpose of the finished product. The strand could be all cotton or all synthetic cellulose-containing fiber in various tightnesses of twist and various numbers of plies, according to the treatment to be given it and the

purpose of the product into which it is to be made.

In one form of my invention, in which I start with a cellulose-containing strand, I prefer to employ a single or multiple-ply strand consisting entirely of vegetable fiber, such as cotton, or a mixture thereof with one or more synthetic fibers such as, but not limited to, rayon, nylon, or glass.

An apparatus for carrying out one form of my invention is shown for illustrative purposes in the accompanying drawings. Any number of filaments may be processed simultaneously, and, accordingly, I may provide one or more spools 20, only one being illustrated for the sake of simplicity. Accordingly the various rollers herein-after referred to may be formed to accommodate the desired number of strands simultaneously. For initially guiding the strands 21 I may provide banks of guide eyes 22, 23, from the latter of which the strands, of which only one is shown for simplicity, pass down under and in grooves 25 of a grooved roller 26, which is held against racing as by a brake spring 27, made of wire or otherwise, and anchored to a bracket 28 extending from the roller-carrying axle 29, the spring bearing frictionally against the roller. The grooves 25 hold the various strands 21 apart. From this grooved roller 26 the strand passes about a friction or traction roller 32 supported by and at one end of an acid-resistant tank 36 containing an acid having the property of converting cellulose to a gelatinous state, for example a weak sulphuric acid solution 38 which may be cold or at room temperature and may consist of two parts of commercial sulphuric acid (which is generally about 97% of full strength) to one part of water by volume. The tank 36 may be lead-lined. Then the strand passes under and in a groove of a grooved roller 42 disposed over the surface 43 of the acid. The grooved roller 42 and traction roller 32 are preferably geared together as at 48, the arrangement being such that the linear speed of the strand-engaging portions of the rollers 32 and 42 will be the same and therefore the grooved roller 42 will not add to the tension on the strand and both rollers will carry the strand and thus act as a conveyor. The strand passes down from the grooved roller 42 and under and in contact with a grooved roller 50 immersed in said solution, runs to a second immersed grooved roller 52, and then rises out of the solution and passes about a grooved roller 54 preferably disposed over the surface of the solution, the grooved rollers being acid-resistant and preferably of light weight to reduce resistance to turning. From the grooved roller 54 the strand passes over a second traction roller 55, preferably clear of the acid tank 36 and geared to the roller 54 as at 56, then, if desired, over a grooved guide roller 57 to insure against wrapping of the strand about the second traction roller 55, which might otherwise occur if the tension on the strand is low or the speed of the strand is high. In other cases the roller 57 could be omitted, in which event the strand may pass from the traction roller 55 directly to the tank therebelow. Then the strand passes down outside of the acid tank 36 and into a second tank 58 containing preferably circulating water 59, which may be cold, for rinsing the acid-treated strand, the water being supplied at 60 and discharged at 61. The strand then passes under a grooved roller 62 immersed in the water and runs under a second immersed grooved roller 64 from which it passes to a grooved roller 66 disposed outside

of the water. From the grooved roller 66 the strand passes about a third traction roller 68, these rollers being preferably geared together as at 48.

5 The acid tank 36 may have a drain plug 69 arranged over the water tank 58 from which the circulating water discharges to sewerage.

Before the strand is treated it is dry and will stand more tension than when in the acid bath. 10 When treated by the acid, care must be taken to avoid undue pulling of the strand. If there were no traction by the first traction roller 32, the strand would be under direct tension between the spool 20 and the second traction roller 55, and 15 the resistance offered by the spool and other parts before the strand reaches the first traction roller 32 might be sufficient to strain the part of the strand in the acid excessively and cause it to weaken or break. By providing traction (by 20 means hereinafter described) at the first traction roller 32, which, as pointed out above, cooperates with the grooved roller 42 to serve as a conveyor, and by driving the second traction roller 55 at a surface speed no greater than that of the first traction roller 32, they cannot tension the portion of the strand in the acid, and thus the whole system of rollers from the first traction roller 32 to the second traction roller 55 acts as a conveyor. In practice, to obviate the necessity for precision 25 manufacture, it may be advisable to construct the parts so that the surface speed of the second traction roller 55 is definitely less than that of the first traction roller 32. In such event provision should be made for slippage of the strand past the second traction roller 55, as will appear.

30 The third traction roller 68 should preferably be synchronized with the first traction roller 32, in which event there would be a slight slippage of the strand over the second traction roller 55.

35 If the third traction roller 68 runs somewhat faster than the first traction roller 32, there will be some slippage of the third traction roller past the strand, tending to increase the tension somewhat. This may not be harmful for strong 40 strands but may be undesirable for weak strands such as yarns, for example. Where the strength of the strand material permits, it may be advisable to run the third traction roller 68 slightly faster than the first traction roller 32, since precision manufacture is thereby obviated. The 45 third traction roller 68 preferably does not run slower than the first, since the strand may accumulate therebetween, or, if a succeeding traction roller runs fast enough to take up the slack, 50 there may be excessive drag on the strand because the pull of such succeeding traction roller will have to cause the strand to slip about both the second and third traction rollers 55 and 68.

55 Now the strand passes from the third traction roller 68 outside the water tank 58 and may, if desired, pass over a grooved roller 69 having the same function as the grooved roller 57, whence the strand enters a third tank 80 containing a preferably weak solution or bath of an alkali, for example ammonia 82, which may be at room temperature. A 5% solution is satisfactory, the purpose being to neutralize any free acid which the water may have failed to rinse off the strand. The strand now passes down into the ammonia solution 82 and under an immersed grooved roller 84 from which it runs in the ammonia bath and passes under another immersed grooved roller 86 and thence out of the solution. The strand then passes about a grooved roller 88 outside of the solution, and then about a fourth traction

70 75

roller 90, geared to the roller 88 as at 48. The speed of the fourth traction roller 90 is preferably the same as or less than that of the third traction roller 68, for the reasons noted above, with respect to the relation of the second traction roller 55 to the first traction roller 32.

From the fourth traction roller 90 the strand may, if desired, pass over a grooved roller 92 having the same function as the grooved roller 51, and then passes into a fourth tank 94 containing 10 a rinse bath of circulating water 86, which may be cold if desired, supplied as at 87 and discharged as at 88. The supply for both water tanks may be common, as by means of the pipe 89, and the discharge for both water tanks may be common, as by means of the pipe 100. The strand then passes under a second immersed grooved roller 102, departs from the water, passes about another 15 grooved roller 103, and then over a fifth traction roller 104. The speed of the fifth traction roller 104 is preferably the same as or somewhat greater than the speed of the third traction roller 68.

The ammonia tank 80 may have a drain plug 105 arranged over the second water tank 94 from which the circulating water discharges to sewerage.

The vertical arrangement of tanks makes for compactness, small floor space requirements and 30 eliminates rollers, which would be required, if the tanks were on the same level, to prevent the strands from touching the entering edge of the second and succeeding tanks. The staggered arrangement enables drainage from the traction 35 rollers 55, 69 and 90 to drip into the next lower tank.

An idler roller 106, preferably of soft rubber, rests by gravity on the fifth traction roller 104 and cooperates therewith to form a wringer for 40 removing excess but not all of the water adhering to the strand emerging from the second water tank 94, and also applies further traction. If the fifth traction roller 104 runs faster than the fourth traction roller 90 the fifth traction roller 45 will slip past the strand, and the drag will not be excessive, due to the lowering of frictional resistance because of the wetness and the yieldability of the idler roller 106.

The strand emerging from between the traction and wringer rollers 104 and 106 has a core consisting at least in part of cellulosic material not affected or at any rate not substantially affected by the acid, covered by a gelatinous or gummy film or coat about which there is or may be a slight amount of moisture not removed by the wringing. The strand is then passed about a smooth grooved roller 108 and from there into a tank 110 containing sodium silicate (water glass) 112 or other coating material, preferably synthetic and preferably heat resistant, such as phenol formaldehyde. This tank is preferably rather deep and shaped so that the area at the surface of the silicate is small so as to minimize drying. Drying of the silicate may be further obviated by providing a removable lid 114, having openings 116 only for the entrance and departure of the strands. A grooved roller 118 immersed in the silicate solution 112 guides the strands through the solution. The strand after passing under the grooved roller 118 emerges from the sodium silicate solution and passes over another smooth grooved roller 120.

The strand then passes over sixth and seventh traction rollers 122 and 124 on which may rest

wringer rollers 126 and 128, all such rollers 120, 122, 124, 126 and 128 being removably supported in a steam or vapor chamber or box 129, for which an inlet pipe 130, connected to a suitable steam or vapor supply (not shown) may be provided. The box 129 may have a removable cover 131. The rollers 122, 124, 126 and 128 in the chamber 129 serve to remove excess sodium silicate from the strand, while leaving a film of the silicate thereon, and prevent slackening of the strand between them and the fifth traction roller 104. Either or both of the gravity rollers 126 and 128 may be omitted, according to conditions. Each provides additional traction and wrings some of the silicate off the strand. The seventh traction roller 124, with or without the superimposed roller 128, prevents the tacky silicate coating from causing the strand to wrap around the sixth traction roller 122. The seventh traction roller 124 preferably runs as fast as the fifth traction roller 104 or faster. The sixth traction roller 122 may run slower, as fast as or faster than the fifth traction roller 104 but not faster than the seventh roller 124. If the sixth traction roller 122 runs slower than the seventh traction roller 124, the strand will of course slip. Thereafter the strand passes over a grooved whipping wheel 132 from which it gravitates toward an endless conveyor belt 134, preferably waxed to prevent the silicate coated strand from adhering to the belt.

The traction and gravity wringer rollers are preferably made of soft rubber, synthetic or otherwise. The various traction rollers may be suitably driven, as by chain and sprocket, or by belt and pulley, although the grooved rollers associated and cooperating with traction rollers are preferably geared thereto. These grooved rollers could be friction-driven by the respective traction rollers, but this may be undesirable because if a strand creeps out of a groove and enters between frictionally engaged portions of a grooved roller and a traction roller, the strand will be bound and unable to slip, rendering it likely to break. A suitable arrangement is shown in Fig. 6, for example.

The chamber 129 is provided to furnish a moist atmosphere of steam or other vapor, hot or cold, which condenses on the silicate coat, the rollers 120, 122, 124, 126, 128 and the whipping wheel 132, so that the silicate on the strand and said rollers and wheel will not cause the strand to adhere to the rollers and wheel and also so as to prevent too rapid drying of the silicate on the strand. The moisture also dilutes the silicate on said rollers and wheel so that the diluted silicate drains off, thus cleaning the rollers and wheel. A baffle 136 provided on the box 129 prevents the draining diluted silicate from draining into the silicate tank 110 and guides it into a suitable drain or container 138.

The purpose of the whipping wheel 132 is to prevent the strand from wrapping about the next preceding (seventh) traction roller 124 and about itself. If the wheel 132 were circumferentially continuous, as are the rollers, then the strand, due to the fact that it is wet, would wrap about the wheel and not drop onto the conveyor 134. Therefore the wheel 132 has circumferentially spaced strand-engaging parts, such as the blades 138, formed with strand-guiding and separating grooves or notches 140. However, if the surface speed of the strand-engaging portions of the blades were no greater than that of the seventh traction roller 124, then, due to the resulting relatively small amount of contact between the whip-

ping wheel 132 and the strand, the wheel would exert a relatively small amount of traction on the strand, insufficient to prevent the strand from wrapping about the traction roller 124. To overcome this drawback, I rotate the whipping wheel 132 at such a rate that the notches 140 of the wheel move at a substantially greater speed than, and hence slip relative to, the strand engaging the same while exerting a substantial tractive and whipping force thereon, sufficient to pull the strand taut from the next preceding traction roller 124. A speed ratio of about 3 to 1 has been found satisfactory but the ratio may be increased or decreased as desired. Six blades 138 equally spaced have been found satisfactory, but the number may be smaller or greater as desired. The blades are preferably quite thin to afford relatively small surface engagement with the strands, and each strand-engaging surface of the blades is smooth and rounded to avoid excessive traction and obviate snagging of the strand.

Due to the whipping action, the strand assumes a substantially curved shape about the whipping wheel 132, as shown at 142, and drops from the wheel onto the conveyor belt 134. The conveyor belt 134 is preferably made of screening or perforated sheet material or any other material, metal or otherwise, which will allow the passage of air therethrough, and its outer surface is coated with wax, paraffin or similar material to which the moist strand is non-adherent. The conveyor belt 134 may be mounted on suitable drums or rolls 144. Between the upper and lower runs of the conveyor belt 134, I provide a chamber 146 perforated as at 148 at the top thereof to discharge cool or room temperature dry air which is delivered thereto as by a fan or from a source of compressed air (not shown). This dry air passes through the upper run of the conveyor belt and into contact with the strand. The air is dry for the purpose of drying the silicate film on the strand, and is cool in order not to soften the wax or like coat on the conveyor belt. The air is preferably blown with substantial force so as to raise the strand, as shown at 152, enough to allow the entire surface of the strand to come in contact with the air so that the drying of the strand will be circumferentially uniform.

The conveyor belt is preferably run at substantially less speed than that at which the strands 21 drop from the whipping wheel 132 so that the strands will accumulate on the conveyor belt, rather than string out in a straight line, although the speeds may be substantially synchronized if accumulation is not desired. When the strand accumulates, it naturally forms into curls, as shown at 154, which lie in substantially horizontal planes flat over the conveyor belt, and has substantially the appearance, along the conveyor, of a continuous penmanship exercise of the letter "O," written according to the Palmer method, the spacing of consecutive turns or coils depending on the relative speed of the belt.

It is desired that upon being discharged from the conveyor belt 134 the strand should be substantially non-tacky, yet sufficiently soft so that the silicate coating will not crack when bent or subjected to crimping. Therefore the conveyor belt 134 should be of such length as to insure that the strand will be in the proper condition when discharged, bearing in mind, of course, that the speed of the conveyor belt is also a factor.

The primary speed factor, however, is that of the strand in the acid tank 36.

From the conveyor belt 134, the strand passes between crimp rollers 156 and 158, one roller being adjustable toward and away from the other, to provide between the cooperating teeth thereof ample space for the reception and crimping of the strand. If the conveyor belt is run at such a speed that the strand is substantially straight or at least uncoiled, on the conveyor, substantially only the thickness of the strand need separate the teeth of the crimp rollers. However, if the strand has been allowed to accumulate, i. e. curl, on the conveyor, the strand has one or more portions lying one on top of the other or others, and, when there are two or more strands, neighboring strands, if sufficiently close, will overlap, with the result that two or more strand thicknesses must be accommodated between the crimp rollers and hence the spacing must be correspondingly greater. The crimp rollers are preferably driven by means of gears 160 which will be more or less tightly meshed according as the spacing of the crimp rollers is less or greater. Adjustment may be effected in any suitable manner. The strand upon discharge from the crimp rollers has the shape it had upon entering the crimp rollers, modified by the corrugating imparted to it by the crimp rollers. At this time the strand is non-tacky but still somewhat soft. When operating on strands treated as above described, the crimp rollers are preferably unheated, i. e., at room temperature, for example, since heating will unduly harden the silicate coat and then the rollers will crack the coat and pulverize the coat at the cracks. The powdering is undesirable, since it will clog the crimp rollers and necessitate cleaning of adjacent parts, as well as the strand itself, especially when the strand is to be used as a filter in an air cleaner, for example. The crimp rollers 156 and 158 should run at substantially the same or at a reduced surface or pitch speed relative to the first conveyor belt 134 in order to preclude pulling the strands, i. e., causing the strands to slide off the conveyor belt. From time to time the strands will accumulate at the first meshing teeth, and then the accumulations will be drawn in and crimped. This makes for a more snarled and therefore desirable final product.

The strand thus crimped is preferably baked. To this end it passes from the crimp rollers onto a second conveyor belt 180. This conveyor belt is disposed below the place at which the strand is discharged from the crimp rollers, but preferably as close as practicable. The reason for this is that if the corrugated strand were to have a long descent, it might tend by its own weight to straighten and thus nullify, at least in part, the effect of the crimp rollers and of the curling and twisting which occurred when the strand was deposited on the first conveyor belt 134. A descent of about one inch to about four inches has been found satisfactory for different materials and weights of materials, although the optimum distance may be more or less, and may be easily ascertained by observation and trial for any type and weight of strand material.

The second conveyor belt 180 is preferably formed of a strong woven or other open mesh metal such as steel or other suitable strong and heat-resistant material. The belt 180 is mounted on drums or rollers 182, and a heating means such as, for example, an electric hot plate 183, having a resistance wire 183a, or gas burner (not

shown) is arranged to heat the upper run of the belt 180. The heat applied is such as to bake the entire strand dry, through and through, without injury. Of course the length of the belt 180 and the speed at which it is run are factors also. The belt should move no faster, and preferably moves slower, than the strands as they are deposited thereon from the crimp rollers 156 and 158. If the belt 180 should run faster, the strand would be pulled by the belt and thus tend to uncrimp and uncurl. It may be best to bake the material slowly in order to insure that the surface of the strand is not excessively heated and thus injured and to obtain substantially uniform drying throughout the thickness of the strand. The baking temperatures are readily ascertainable by trial and error, depending on the strand material. For example, an all-cotton thread treated as herein outlined has been found to turn out satisfactorily if, while in motion, it is baked at a temperature of about 300° F. for a period of about one minute. A thinner all-cotton thread of the same number of plies and twists and so treated should have a lower baking temperature to avoid excessive heating. Mixtures of vegetable and synthetic fibers treated as above may require still other baking temperatures, depending on their resistance to heat. The selected temperature in any event should not exceed and preferably should be below the lowest safe temperature of the strand in question.

Suitable provision may be made for controlling the temperature of the heater, as, for example, a rheostat 185 in the circuit of the heater resistance element 183a and graduated to temperatures of, say, the upper run of the belt 180, together with an adjustable thermostat 186.

The baking step has a shrinking effect, causing the strand to permanently kink, as shown at 187, at relatively short and irregular intervals, on the order of about $\frac{1}{4}$ " more or less to about 1" more or less, independently of and without otherwise substantially affecting the curling and crimping.

The baking step completes the process of making one form of filament 188 according to my invention. In this form the filament is highly resilient and flexible, with a hard, rough, friction surface film 189, an inner relatively soft sheath 190, and the core 191, entirely or partly of cellulose, the filament being kinked as shown at 187 at irregular intervals, corrugated, and, if the strand is curled, or curled and twisted, on the first conveyor 134, the filament is also curled, or curled and twisted. If the filaments are allowed to drop from the baking conveyor 180, or from a roller 194 beyond the conveyor 180, in a heap or pile 195 on a floor 196 or other support, they will become snarled into a shapeless mass which can be pressed to desired shapes according to the use to which the filament material is to be put, and in such shapes the masses will be resilient and substantially shape-retaining. The interlocking of the interengaged portions of the filament is greatly enhanced by the shape and roughness imparted to the filament by the treatment described, and, once packed, there will be substantially no slipping or shifting of the engaged portions. Moreover, because of this treatment, the engaged portions will have substantially point, rather than line, contact, so that the material can be greatly compacted and yet have adequate air space or cells or pores so that dust will not clog it.

When pressed into a shape for use as a filter in an oil bath type carburetor air cleaner, for exam-

ple, my filament material is highly efficient. One reason for its efficiency is the fact that it is curled, corrugated, kinked and rough-surfaced, the surface including tiny projections and valleys resembling, to the touch, minute serrations. By reason of the surface roughness, the oil clings to the ridges and valleys, and, by reason of the curling, crimping and kinking, the number of intersections, to which the oil also clings, is increased so that the oil encounters considerable resistance to flow up in the filter. Thus for a given oil bath air cleaner, the maximum amount of air free of oil and solids that can be drawn through the filter compares favorably with that which obtains when hair, wire and other conventional filter material is used. In addition to increasing the resistance to the rise of the oil, the roughness of the filament surface offers a longer path of contact with the air, so that more solids have an opportunity to be caught and retained than would be the case if the filament were smooth. Moreover, where the oil does not happen to cling to the filament, the roughness of the bare filament itself offers places for hooking and catching and retaining solids from the air. The curling, crimping and kinking augment these desirable effects.

A filter made of this material, also, by reason of the fact that it is curled, crimped, kinked and rough surfaced, retains the oil for a longer period than other filter materials, a result which is important because oftentimes the idling speed of an engine is so low as to be insufficient to draw the air with a high enough force to raise the oil from the oil bath up into the filter to a sufficient extent to have any substantial air filtering effect. Moreover, owing to its resilience and shape-retaining property, such filter will not pack or mat down after a considerable period of use, so that the air passages remain fully open indefinitely and thus not only permit the air to be drawn therethrough readily but also enable the oil and solids to be readily and thoroughly washed from the filter. The filter can be made from one or more continuous filaments which can be spun as on a spool to shape as they are discharged from the baking conveyor 180, whereas other material, such as hair and some fibers, because of their relatively short lengths, require more handling and operations to produce the final product. The resilience thus obtained is lacking in filters made with the short hairs etc. now available. Some of the short hairs and fibers become separated and pass out with the air, which of course cannot be tolerated.

Owing to the silicate coat, the filament produced as above described is capable of withstanding the high temperatures to which it is necessarily subjected when used, for example, as a filter in a carburetor air cleaner, due to the heat of the engine, or in connection with a hot air furnace. In an air conditioning system, where the filter is coated with a dust-catching liquid, such as oil, the high efficiency of my material will be apparent from the above.

These filaments can be pressed into bats or can be used in loose or bulk form for heat insulation purposes. In loose or bulk form it is also useful as padding for upholstery and other purposes.

If desired, glass, mineral wool, asbestos fibers, ultra short hair such as hog hair, or other relatively short fibers may be dropped from a suitable hopper 200 onto the first conveyor belt 134 substantially at 202, rearwardly of the place at which the strands 21 drop from the whipping wheel 132, so that as such fibers are carried along by the

conveyor 134 such strands will drop onto the fibers. Inasmuch as the strands are tacky at this point, the fibers will adhere to the strands. The adjacent end 204 of the dry air chamber 146 is spaced forwardly of the place 202 so that the air blown up from such chamber will not affect the fibers before they reach the strands. Thus, when such air is blown upward, it presses the fibers against the tacky strands thereabove, thereby increasing the adhesion of and more firmly mating the fibers to the strands. The fibers 199 are preferably dropped onto the conveyor 134 in sufficient quantity to form a layer so that as many of the fibers as possible will adhere to the tacky strands, but of course the concentration of fibers may be varied as desired. If desired, the surplus fibers may be drawn off by suction into a hood 206 or other means to be collected and reused if desired. The remainder of the process may be the same as that described above, the temperature and duration of the baking being corrected if necessary in accordance with the properties of the fibers used.

The auxiliary hairs and fibers are relatively inexpensive and provide bulk and resilience, so that filters, insulation and packing material made from them combined with strands of my invention are relatively less expensive than when made entirely of strands. For purposes of insulation and packing, the composite construction may be preferred, as the efficiency should be substantially the same as or better than when strands only are used and the cost is less. For filtering, the all-strand construction may be preferred because of the surface roughness of the strands.

In accordance with another form of my invention I may start with a thermoplastic strand and corrugate it. One way of accomplishing this result is by crimping the strand, using heated crimp rollers. The crimp rollers 156 and 158 may be used, and for this purpose one or each crimp roller may be hollow, as shown at 208, to accommodate an electric heating element 209, which may be held stationary by suitable supporting means (not shown) while the crimp rollers turn. The temperature of the heating elements 209 may be controlled as by a rheostat 210 and adjusted so that the external surfaces of the teeth of the crimp rollers are hot enough to apply the heat necessary to soften the strand to a moldable state so that the teeth may impart thereto a corrugated shape as shown at 212. If desired, the strand, after leaving the crimp rollers 156 and 158, may be allowed to cool sufficiently to retain the shape imparted thereto and be collected in a heap on the floor or be wound on a spool or otherwise collected. This material possesses inherent resilience which is enhanced by the crimping process, and the corrugations enable the material to snarl and interlock, so that it will pack yet tend to retain its shape as long as it is below its softening temperature, and thus may serve usefully as a filter, padding and the like.

To render the corrugated thermoplastic material 212 even more efficient, I prefer to add a heating step which may be similar to the baking step above described. Accordingly the corrugated material 212 may be deposited directly, or at any other time after leaving the crimp rollers 156 and 158, onto the heated conveyor belt 180, the temperature of the belt being preferably sufficiently high to cause the material, which will lie free on the belt, to squirm and wriggle, and kink and form into miscellaneous relatively small curls, bends and knots, at irregular and close in-

tervals of roughly $\frac{1}{8}$ " more or less, as shown at 214. These formations added to the corrugations greatly increase the resilience and the tendency to snarl and interlock, and hence render filters, etc., made therefrom more efficient.

The temperatures of the crimp rollers 156 and 158 and the baking conveyor belt 180 will vary with the characteristics of the thermoplastic used. The temperature of the crimp rollers should not exceed that which will soften the strand sufficiently to enable the corrugations to be formed and remain therein. The temperature of the baking conveyor belt should be slightly below the melting point of the thermoplastic strand.

The apparatus may be driven by any suitable mechanism. For example, I may provide a motor 220, for which a hand switch is conveniently arranged as at 221, with a gear reduction 222 operating at relatively low speed a pulley 224, which, through a belt 226, drives a pulley 228. A smaller pulley 230 on the same shaft with the pulley 228 operates through a belt 231 to drive a pulley 232 which, through the associated smaller pulley 234 and a belt 235, drives a pulley 236 on the same shaft with the rear drum 144 of the rear or drying conveyor 134. A smaller pulley 238 on the same shaft with the pulley 236 receives a belt 240 by which to drive a pulley 242 on the same shaft with the rear drum 182 for the baking conveyor 180. The conveyor transmits the drive from the rear drum to the forward drum thereof, and a pulley 244 on the same shaft with said forward drum operates through a belt 246 to drive a pulley 248 whereby to turn the discharge roller 194. A pulley 250 on the same shaft with the pulley 242 operates through a belt 252 to drive a pulley 254 on the same shaft with the crimp roller 158, which, by means of the gears 160, drives the crimp roller 158.

On the same shaft with the pulleys 228 and 230 is a third pulley 232 operating through a belt 260 to drive a pulley 262. On the same shaft with the pulley 262 is a second pulley (not shown) which operates through a belt 266 to drive a pulley 268 which is on the same shaft with and therefore drives the fifth traction roller 104. A second pulley 270 on the same shaft with the pulley 268 operates through a belt 272 to drive a pulley 274 which is on the same shaft with and therefore drives the third traction roller 68. A second pulley 276 on the same shaft with the pulley 274 operates through a crossed belt 278 to drive a pulley 280 which is on the same shaft with and therefore rotates the first traction roller 32.

A third pulley (not shown) on the same shaft with the pulley 262 operates through a crossed belt 286 to drive a pulley 288. On the same shaft with the pulley 288 is a second pulley (not shown) which operates through a belt 290 to drive a pulley 292 whereby the fourth traction roller 90 is driven. A second pulley 293 on the same shaft with the pulley 292 operates through a belt 294 to drive a pulley 296 whereby the second traction roller 55 is driven.

A fourth pulley 300 on the same shaft with the pulley 262 operates through a belt 302 to drive a pulley 304 on the same shaft with a second pulley 306 operating through a belt 308 to drive a pulley 310 on the same shaft with and therefore driving the sixth traction roller 122. A second pulley 312 on the same shaft with the pulley 310 operates through a belt 314 to drive a pulley 316 on the same shaft with and therefore driving the seventh traction roller 124.

A third pulley 326 on the same shaft with the pulleys 324 and 328 operates through a belt 322 to drive a pulley 324 on the same shaft with and therefore driving the whipping wheel 132.

While there is shown and described herein certain specific structure embodying the invention, it will be manifest to those skilled in the art that various modifications and rearrangements of the parts may be made without departing from the spirit and scope of the invention, and that the same is not limited to the particular forms herein disclosed, except insofar as indicated by the appended claims.

I claim:

1. A process of making a kinky filament, comprising the steps of taking a cellulose strand, immersing said strand in a bath of sulfuric acid solution, removing said strand when it has acquired a gelatinous outer layer, but before the core of said strand has been substantially treated by said acid solution, rinsing said gelatinous coated strand in water until the same is substantially free of acid, immersing said strand thereafter in a bath of weak ammonia solution to neutralize any acid remaining on said strand after the water rinse, rinsing said strand thereafter in water until the ammonia is washed off, then removing excess liquid from said strand, thereafter immersing said strand in a bath of sodium silicate until it has acquired a film of said sodium silicate, moistening said film, curling the filament while said film is moist, partially drying said film, corrugating the curled filament while partially dry, and thereafter baking said filament to permanently set the curls and corrugations and permanently kink the strand.

2. An apparatus for forming a kinky filament, comprising means for treating a strand containing cellulose with sulfuric acid to render the exterior of the strand gelatinous, means for removing excess liquid from the gelatinous coat, means for thereafter applying a film of sodium silicate to said coat, means for thereafter removing excess sodium silicate from said film, means for thereafter applying moisture to said strand, means for intermittently subjecting successive portions of said strand, while maintained in moistened condition, to a combined slipping and pulling action, a conveyor on which the strand is then allowed to drop, means for drying said strand, while on the conveyor, to a moldable non-tacky state, means operable upon said strand after said strand leaves said conveyor and while said strand is in a moldable non-tacky state for crimping said strand, a second conveyor disposed closely adjacent said crimping means and on which the crimped strand descends from said crimping means, means for maintaining said second conveyor at a temperature in the neighborhood of 200° F., more or less, for baking said strand to a dry, relatively hard, resilient, kinky and crimped filament.

3. An apparatus for making a strand into a kinky relatively stiff resilient filament, comprising means for treating the exterior portion of a strand containing cellulose with sulfuric acid to render the same gelatinous, means for coating said gelatinous portion with a film of sodium silicate, means for coiling the strand so coated, a conveyor for receiving the coiled strand, means for baking the film-covered strand, said conveyor being operative to deliver the strand to said baking means, and means for preventing the film from adhering to said conveying means.

4. An apparatus for making a strand into a

kinky relatively stiff resilient filament, comprising means for treating the exterior portion of a strand containing cellulose with sulfuric acid to render the same gelatinous, means for coating said gelatinous portion with a film of sodium silicate, means for baking the film-covered strand, means for conveying the strand to said baking means, means for preventing the film from adhering to said conveying means, and means for rendering the strand non-tacky, said conveying means including means for crimping the strand while the strand is still in a moldable state.

5. An apparatus for conveying a plastic strand having a tacky surface, comprising a roller for feeding such a strand, and a rotary member toward which the strand proceeds from said roller, said rotary member having circumferentially spaced blades having circumferentially aligned notches for receiving and guiding the fed portion of the strand, and means for rotating said member so that the strand-engaging portions of said notches move in the same direction as and substantially more rapidly than the engaged portions of the strand, whereby said strand-engaging portions engage successive portions of the strand intermittently and with a wiping action so as to whip the strand and prevent the strand from wrapping about said roller and about said rotary member.

6. A process of making a kinky filament, comprising the steps of taking a strand containing cellulose, immersing said strand in a bath of sulfuric acid solution, removing said strand when it has acquired a gelatinous outer layer, but before the core of said strand has been substantially treated by said acid solution, rinsing said gelatinous coated strand in water until the same is substantially free of acid, immersing said strand thereafter in a bath of weak ammonia solution to neutralize any acid remaining on said strand after the water rinse, rinsing said strand thereafter in water until the ammonia is washed off, then removing excess liquid from said strand, thereafter immersing said strand in a bath of sodium silicate until it has acquired a film of said sodium silicate, moistening said film, coiling the filament while said film is moist, partially drying said film, corrugating the coiled filament while partially dry, and thereafter baking said filament to permanently set the coils and corrugations and permanently kink the strand.

7. An apparatus for forming a coiled filament, comprising means for treating a strand containing cellulose with sulfuric acid to render the exterior, only, of the strand gelatinous, means for removing excess liquid from the gelatinous coat, means for thereafter applying a film of sodium silicate to said coat, means for thereafter removing excess sodium silicate from said film, means for moving said strand from the last-mentioned removing means, means affording an atmosphere of steam for said strand and moving means, and means for intermittently subjecting successive portions of said strand in said atmosphere to a combined slipping and pulling action, whereby said strand, upon thereafter being deposited on a support, forms into coils.

8. An apparatus for forming a coiled filament, comprising means for treating a strand containing cellulose with sulfuric acid to render the exterior, only, of the strand gelatinous, means for removing excess liquid from the gelatinous coat, means for thereafter applying a film of sodium silicate to said coat, means for thereafter removing excess sodium silicate from said film, means

for moving said strand from the last-mentioned removing means, means affording an atmosphere of steam for said strand and moving means, means for intermittently subjecting successive portions of said strand in said atmosphere to a combined slipping and pulling action, whereby said strand, upon thereafter being deposited on a support, forms into coils, a conveyor on which the strand is then allowed to drop, means for drying said strand, while on said conveyor, to a moldable non-tacky state, and means operable upon said strand after said strand leaves said conveyor and while said strand is in a moldable non-tacky state for crimping said strand.

9. An apparatus for forming a coiled filament, comprising means for treating a strand containing cellulose with sulfuric acid to render the exterior, only, of the strand gelatinous, means for removing excess liquid from the gelatinous coat, means for thereafter applying a film of sodium silicate to said coat, means for thereafter removing excess sodium silicate from said film, means for moving said strand from the last-mentioned removing means, means affording an atmosphere of steam for said strand and moving means, means for intermittently subjecting successive portions of said strand in said atmosphere to a combined slipping and pulling action, whereby said strand, upon thereafter being deposited on a support, forms into coils, a conveyor on which the strand is then allowed to drop, means for drying said strand, while on said conveyor, to a moldable non-tacky state, means operable upon said strand after said strand leaves said conveyor and while said strand is in a moldable non-tacky state for crimping said strand, a second conveyor disposed closely adjacent said crimping means and on which the crimped strand descends from said crimping means, and means for baking said strand to a dry relatively hard, resilient, kinky and crimped filament.

10. A process of making a filament, comprising the steps of taking a thread containing cellulose, reacting the exterior portion, only, of said thread with sulfuric acid solution until said exterior portion is gelatinized, coating said gelatinized portion with a film which, when dry, is heat-resistant, oil resistant, resilient, and vermin repellent, and stiffens the thread, coiling the thread while it is moist, corrugating the coiled thread while the film is still moist, baking the thread until dry to thereby permanently set the coils and corrugations, and

continuing the baking until relatively sharp pointed bends are formed at intervals along the thread.

Certificate of Correction

Patent No. 2,470,039.

May 10, 1949.

EDWARD E. LOVIG

It is hereby certified that error appears in the printed specification of the above numbered patent requiring correction as follows:

Col. 16, line 31, list of references cited, for the patent number "1,660,083" read *1,666,083*;

and that the said Letters Patent should be read with this correction therein that the same may conform to the record of the case in the Patent Office.

Signed and sealed this 18th day of October, A. D. 1949.

[SEAL.]

THOMAS F. MURPHY,
Assistant Commissioner of Patents.
